UNITED STATES PATENT OFFICE.

FRANS BIRGER STAFSING, OF STOCKHOLM, AND CARL EGNÉR, OF KLIPPAN,
SWEDEN.

TELEPHONE SYSTEM.

SPECIFICATION forming part of Letters Patent No. 693,356, dated February 11, 1902.

Application filed July 16, 1900. Serial No. 23,815. (No model.)

To all whom it may concern:

Be it known that we, FRANS BIRGER STAFSING, a resident of 5 Kommendörsgatan, Stockholm, Sweden, and CARL EGNÉR, a resident 5 of Klippan, Sundbyberg, Sweden, subjects of the King of Sweden and Norway, have invented new and useful Improvements in Telephone Systems, of which the following is a specification, reference being had to the drawing 10 and accompanying and forming a part hereof.

It is well known that the operators of a telephone-exchange are often obliged to connect their receiving apparatus to the subscribers' circuits in order to ascertain whether a 15 course has begun or has been finished. This listening, however, is not seldom, to the detriment of the clearness of the sound transmitted and to the displeasure of the subscribers, prolonged for too long a time.

20 The object of the present invention is improvements in telephone systems by means of which the persons using the telephones are enabled to observe whether any undue listening takes place or not. By this means 25 the great advantage is also gained that the operators may be spared being unjustly accused of listening.

The invention consists, briefly, in connecting to the circuit of the operator's receiver of 30 a usual telephone system an extra source of electric current, in such a manner that extra electric currents are sent out in the subscribers' circuits as soon and as long as the receiving apparatus of the operator at the 35 exchange is coupled to the said circuits, and in connecting to the subscribers' circuit some suitable signaling apparatus which will give visible or audible signs when the listening is taking place.

40 The invention further consists in the special combination of parts hereinafter described and claimed.

In the accompanying drawing the figure shows diagrammatically how this invention 45 may be carried out.

Referring to the drawing, *a* *c* and *c* *b* represent two subscribers' circuits of a telephone

system, said circuits being coupled together for telephonic communication between the two subscribers' telephone apparatus *a* and *b*, through the exchange *c*, by means of the usual conducting-cords or the like. By the aid of a switch coupling device *d* the receiving-telephone apparatus *e* of the operator can be coupled to the line for listening, as usual. 55 Connected between a neutral point of the circuit of the operator's receiver *e* at the exchange, inside the said switch *d*, and the ground is a source of electric currents, such as a galvanic battery *n*. Indicators *o*—such as galvanometers, electric bells, or the like—are connected between neutral points of the subscribers' circuits and the ground, as shown. When the switch *d* is closed, the said battery 60 sends out electric currents which act upon the said indicators, so that signals are obtained which show that the operator is listening.

The invention may be carried out in several other ways well understood by persons 70 skilled in the art to which it appertains without departing from our invention.

Having described our invention, what we claim as new, and desire to secure by United States Letters Patent, is—

75 The combination in a telephone system, of an operator's circuit, a switch between said circuit and the line, a source of electric currents connected between a neutral point of the said operator's circuit inside the said switch and the ground, a subscriber's circuit, and a current-indicator connected between a neutral point of the said subscriber's circuit and the ground, substantially and for the purpose set forth.

80 In testimony whereof we have signed our names to this specification in the presence of two subscribing witnesses.

FRANS BIRGER STAFSING.
CARL EGNÉR.
